UNITED STATES PATENT OFFICE.

PETER E. KURNICK, OF SAN FRANCISCO, CALIFORNIA.

COUCH ARMCHAIR.

1,421,260.

Specification of Letters Patent. Patented June 27, 1922.

Application filed December 17, 1920. Serial No. 431,371.

To all whom it may concern:

Be it known that I, PETER E. KURNICK, a citizen of the United States of America, residing at San Francisco, in the county of 5 San Francisco and State of California, have invented new and useful Improvements in Couch Armchairs, of which the following is a specification.

The object of the invention is to provide 10 a relatively simple and comparatively inexpensive chair which may be readily converted by occupant to adapt it for supporting the latter in a reclining position or to perform the functions of a couch, and which 15 may also be readily adapted to serve either as a rocking or standing chair or as a rolling chair; and with these objects in view, the invention consists in a construction and combination of parts, of which a preferred embodiment is shown in the accompanying 20 drawings, wherein:—

Figure 1, is a side view of the structure adapted for use as a rocking chair with the rollers shown in dotted lines in the positions 25 which they assume to hold the chair in a stationary or standing position and with the back shown in dotted lines in its lowered or extended position.

Figure 2, is a plan view. 30 Figure 3, is a front view, partly in section. Figure 4, is a detail section on the plane indicated by the line 4—4 of Figure 1.

Figure 5, is a view of the lower portion of the chair showing the rollers extended to 35 support the chair in position for rolling.

The chair seat 10 is preferably provided with side arms 11 supported by supports 12 and fitted to slide in the seat is a leg extension 13 which in the construction illustrated 40 is provided at its edges with grooves 14 for engaging guides 15 moving inwardly from the depending side bars 16 of the seat. Depending from the seat are the legs 17 carrying the rockers 18 (if the chair is designed 45 to be converted into a rocking chair) and back 19 being pivoted as at 20 between the rearwardly projecting end portions of the seat to adapt it to occupy the upright position indicated in full lines or the substantially horizontal position indicated in dotted 50 lines in Figure 1. The back is connected by means of flexible runners 21 consisting of cables or the equivalent thereof with the leg extension 13, said runners extending through 55 guide grooves 22 in the arm rests and the forward uprights 12 and around suitable

friction pulleys 23 so that the rearward movement of the back causes the forward movement of the leg extension in position, and the tension of the springs 24 which connect the rear edge of said extension with the frame of the seat. Obviously the release of pressure upon the back will permit of the elevation of the latter and the retraction of the leg extension. 60

In order to secure the movable elements consisting of the back and leg elements in their adjusted positions, a clamping means may be employed such as a cam 25 which may be fulcrumed in the arm rest, to bear 70 upon the runner 21 extending therethrough, said cam being provided with a handle 26 which is laterally yieldable and is provided with a terminal stud 27 for engagement with the socket 28 in the side of the arm rest to 75 lock the handle in position when the cam is in position to lock the runner against movement. Obviously the runner may be freed by the occupant of the chair merely by flexing the handles to disengage the studs 27 80 from the sockets 28 and permitting the handles to withdraw the cams from their engagement with the runners.

Pivots mounted upon the supporting frame of the seat as at the points 29 and 30 85 are supports 31 and 32 carrying rollers 33 and 34 adapted to be depressed into contact with the floor or other surface upon which the chair rests, for example, to support the latter in a fixed or standing position when it is desired to prevent oscillating movement upon the rockers 18; and also adapt it to be rolled to still other places when it is desired to move the chair. 90

To this end an operating lever 35 is fulcrumed as at 36 upon the chair structure and is connected at opposite sides of its fulcrumed points with the supports 31 and 32, said lever traversing a rack 37 to which it is secured in its adjusted position. A terminal grip 38 may be provided on the end of the lever within convenient reach of the occupant of the chair and in the construction illustrated, one end of the lever 35 is directly connected to the free end of the support 31 95 while the link 39 is employed to connect an intermediate portion of the seat with the corresponding portion of the support 32 to the end that the movement of the lever in either direction will cause a corresponding movement of the roller supports, or in other words 100 will either elevate or depress the said rollers 105 110

to permit of the supporting of the chair upon its rockers or to secure it against rocking movement but to leave, or so that the chair may be rolled by an attendant.

5 The invention having been described, what is claimed as new and useful is:—

A convertible chair having a seat provided with depending legs and rockers carried at the lower ends of the legs, rear roller carrying supports pivoted to the rockers adjacent the rear ends, forward roller carrying supports pivoted adjacent the front legs, piv-

otally mounted operating levers disposed on opposite sides of the chair, links connecting said levers with the forward roller supports, 15 pin and slot connections between the extremities of the levers and the rear supports, and arcuate racks traversed by the levers for maintaining them in various positions of adjustment in the manner and for the 20 purpose specified.

In testimony whereof he affixes his signature.

PETER E. KURNICK.
